UNITED STATES PATENT OFFICE

97,963

DESIGN FOR A SUIT COAT

Isidore Tomkin, Brooklyn, N. Y., assignor to Eagle Clothes, New York, N. Y., a firm

Application October 9, 1935, Serial No. 58,892

Term of patent 7 years

To all whom it may concern:

Be it known that I, Isidore Tomkin, a citizen of the United States, residing in Brooklyn, county of Kings, and State of New York, have invented a new, original, and ornamental Design for a Suit Coat, of which the following is a specification, reference being had to the accompanying drawing, forming part thereof.

In the drawing:

The characteristic feature of my design resides in two series of short projecting ribs extending substantially perpendicular to the plane of the garment about the side pockets of the coat, and two series of projecting ribs arranged diagonally relative to each other and on opposite sides of a central vertical pleat, the ribs of each series being in parallel relation.

What is claimed is:

The ornamental design for a suit coat, as shown and described.

ISIDORE TOMKIN.
